UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLE-NEEDLE DETECTOR.

Application filed January 5, 1926. Serial No. 79,483.

This invention relates to multiple needle weft detectors for looms and it is the general object of the invention to overcome the inertia of the weights commonly associated 5 with the needle detectors before the latter are engaged by the surface to be detected.

Co-pending application Ser. No. 643,211 shows a plurality of weights one for each needle detector and the purpose of the 10 weights is to hold the needle detectors yieldingly against the yarn being detected. On bobbins wound with very fine yarn it is found that transfers are so infrequent that detectors of the type specified abrade the 15 surface engaged by the detector, the abrasion being intensified by the fact that the weights have an inertia which must be overcome before they can move forwardly. It is the principal object of the present invention to 20 act upon the weights in such a way as to impart motion to them before the yarn of the bobbin engages the needle detectors, thus sparing the bobbin and yarn the necessity of starting the weights in motion.

25 It is a further object of the present invention to begin the forward movement of the weights prior to engagement of the detector with the yarn and to give said weights a quickly retarded movement so that said 30 weights will move forwardly at a slower rate than the yarn is advancing. In slowing down from their starting rates to the condition of rest both the weights and the yarn will move through all rates less than the 35 starting rate, but for the most part they will be traveling at the same rate at different times. There is one time, however, when the rates of movement of both parts will be identical at the same instant and it is a further object of the invention to have the yarn 40 of a full bobbin begin to push against the weights at this instant.

One advantage in the use of weights instead of individual springs for the needle detectors is that the weights, in resisting an increase in velocity, aid the needle detectors in penetrating a very thin layer of yarn which they could not penetrate if reliance were had on springs alone. It is desirable, 45 however, to have the resistance offered by the weights effective only as the bobbin nears

exhaustion. It is a further object of the invention not only to move the weights as previously stated but also to provide for their desired action on the needle detectors 55 as exhaustion approaches. This result is accomplished by causing the weights to retard more quickly than the yarn after the instant when both are traveling at the same rate of speed. As previously stated a full bobbin begins to move the weights at the instant 60 when both are moving at the same rate, and from this it will be seen that as the bobbin diameter decreases the bobbin picks up the weights later and later. A partly exhausted bobbin will therefore pick up the weights 65 when they are not moving as fast as the bobbin and the aforesaid action of the weights in resisting an increase in rate of movement will have the desired effect on the 70 needle detectors. This effect increases as the diameter of the bobbin decreases.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a side elevation of a multiple needle weft detector of the common type showing my invention applied thereto, certain parts being in section,

Fig. 2 is a top plan view taken in the direction of arrow 2, Fig. 1,

Fig. 3 is a vertical section on line 3-3 of Fig. 1,

Fig. 4 is a detail view similar to Fig. 1 showing the parts in the position they assume when the lay is on front center, and

Fig. 5 is a diagrammatic view illustrating the rates of speed of the advancing yarn and the weights.

Referring to the drawings it will be seen that I have provided a fixed stand 10 slotted as at 11 to receive a bolt 12 which passes through a support 13, holding the latter rigidly in adjusted vertical position with respect to the stand. The upper end of the support is provided with a rib 14 which extends into a notch 15 formed in the lower

end of the needle carrier 16. A bracket 17 and tension spring 18 hold the carrier 16 yieldingly in operative relationship with respect to the support 13.

5 Said carrier 16 has slidably mounted therein a plurality of needle detectors 19 having rear yarn engaging portions 20 and upper indicating portions 21. Said portions 21 cooperate with an actuator lever 22 which 10 is given a downward motion on detecting beats of the lay at a time when the latter is in its extreme forward position. Said carrier 16 is provided with a stud 23 passing loosely through ears 24 upstanding from 15 said needle carrier. A plurality of weights 25 are mounted for free pivotal motion on stud 23 and have needle engaging portions 26 and weighted portions 27 extending forwardly from the stud 23. A detector with- 20 drawing yoke 28 is also freely mounted on stud 23 for pivotal motion and has a de- pending arm 29 on one side of the carrier 16 and a second arm 30 on the other side of 25 said carrier. The arm 30 is provided with a wing 31 by means of which the yoke 28 may be swung on its pivot at the time of transfer to move forwardly a pin 32 which extends between arms 29 and 30 and behind the upright portion of the needles 19, thus 30 withdrawing the needles out of the path of the incoming bobbin. The lay 33 carries a shuttle S having a bobbin B formed as set forth in Patent No. 1,220,685 and said bobbin is provided with a plurality of spirally 35 arranged openings so disposed that at least one of them will receive a needle detector at substantial exhaustion. So long as sufficient yarn is present the indicating portions 21 will be moved forwardly from under the 40 actuator lever 22 and the latter will descend without interruption, but when the layer of yarn is sufficiently thin to require replenishment one or another of the needles 20 will enter a hole in the bobbin B and the corre- 45 sponding indicating portion 21 will remain under the actuator lever 22 so that descent of the latter is prevented and the indication given to the replenishing mechanism (not shown). The matter thus far described is 50 of well known construction and forms no part of my present invention.

My improvements relate to means moving at a rate of speed different from that of the lay to impart motion to weights 25 and 55 in carrying out my invention I provide a small stand 40 having a slot 41 through which extends a bolt 42 secured to the support 13. Said stand 40 has a rearwardly ex- 60 tends arm 43 provided with a stud 44 on which is mounted a yoked lever 45 U-shaped in form and having sides 46 extending on both sides of the arm 43. Said lever is pro- 65 vided with a pin 47 which extends beyond one of the sides 46 to receive the upper end of a torsion spring 48 coiled around stud 44

and having the other end thereof lying over a stop 49 which serves the double function of restraining the spring and also limiting rearward movement of the lever 45.

A second pin 50 extends between the arms 70 of the lever 45 and has pivoted thereon the rear end of a link 51 having the forward end formed with a slot 52 which receives a stud 53 secured to the arm 29. As shown in Fig. 1 the studs 47 and 50 are spaced apart horizontally an appreciable distance in order to produce a variation in the rates of travel 75 between the bobbin B and the weights 25.

The lay 33 is provided with a shuttle binder 54 which has riveted thereto a clip 55 80 having a forwardly extending slotted arm 56 and bunter 57 is held rigidly in adjusted position on the arm 56 by means of bolt 58. Said bunter 57 has a substantially vertical forward face and is so placed as to engage 85 the stud 47 when the lay advances.

In operation the lay 33 moves forwardly and backwardly in the loom and on each forward stroke bunter 57 engages the stud 47 at a time when the surface of a full bobbin is spaced a short distance behind the ends 20 of needle detectors 19 as shown in full lines in Fig. 1. As the lay advances after engagement of the stud and bunter lever 45 is moved about stud 44 but because 90 of the fact that stud 50 is in front of a vertical line passing through stud 44 stud 50 will retard more quickly than the bunter 57. Through link 51, stud 53 and arm 29, stud 50 imparts motion to the weights 25 and sets 95 the same in motion, thus overcoming their inertia. Because of the fact that the lay has been retarded at a slower rate than the stud 50 the bobbin will gain on the needles 19 and at some point in the advance movement of 100 the bobbin the latter will engage the detectors. This point is preferably chosen when the weights 25 and needles 19 and the bobbins are all moving at the same rate of speed 105 and is indicated in dot and dash lines in Fig. 1. In this way control of the weights is transferred from the bunter to the bobbin while the weights are in motion and when the difference in the rates is at a minimum. This condition preferably exists when the 110 bobbin is full and will have the same surface thereof subjected to repeated impacts with the detectors.

As the lay continues to advance the parts move to the position shown in Fig. 4 and the detectors are subjected to slight pressure 115 due to the weights but the yarn is not required to initiate movement of the weights.

The action just described spares the yarn 120 of any wear and abrasion which would be caused by overcoming the inertia of the weights when the bobbin is full, but it is found desirable to have the detectors strike the yarn a slight blow as exhaustion approaches so that the detectors will penetrate 125 130

a very thin layer of yarn insufficient for continued weaving but sufficiently strong to move the needles forwardly unless the same were resisted in their forward movement. It will be seen that as the layer of yarn on the bobbin becomes thinner and thinner due to continued weaving the time of contact between the surface of the yarn and the detectors will be delayed more and more beyond the point where the weights and the bobbin are moving at the same rate of speed. Under these conditions a partly exhausted bobbin will be moving at a somewhat faster rate of speed than the weights and when impact takes place between the bobbin and the detectors the difference in relative speed will have the effect of a slight blow on the part of the needle detectors. It will be seen that the intensity of the blow increases as the diameter of the bobbin decreases, a desirable condition, but that it is accomplished by mechanism which spares a full bobbin undesirable abrasion and wear.

Fig. 5 illustrates diagrammatically the rates of movement of the bobbin and the weights. In said figure the full lines indicate the position corresponding to Fig. 1 with bunter 57 engaging pin 47 and weights 25 to the right. As the bobbin advances pin 50 moves downwardly along arc C, giving connector 51 a movement which retards more quickly than the bobbin and bunter. The gap between the bobbin B and the end 20 of the needles 19 will therefore close up and the bobbin will overtake and engage the detectors while the weights are in motion and at a time when the detectors and weights are moving at a rate only slightly less than that of the advancing bobbin.

From the foregoing it will be seen that I have provided a multiple needle weft detector having weights for each detector so constructed that the weights are set in motion and their inertia overcome before the yarn engages the detectors and that as the diameter of the bobbin is reduced by weaving the impact between the yarn and the detectors is accompanied by a slight blow due to the fact that the bobbin is moving at a slightly faster rate than the needles.

Having thus described my invention it will be apparent that changes and modifications may be made therein by those skilled in the art without departing from the spirit

and scope of the invention, and I do not wish to be limited to the details herein disclosed, but what I claim is:

1. In a weft detector for looms, a yarn engaging detector member, weighted means to hold said member yieldingly in position to be engaged by a bobbin, means acting prior to engagement between the bobbin and the detector member to set the weighted means in motion and give the same a movement which retards more quickly than the retardation of the advancing bobbin, the rate of advance of the weighted means and detector member and also the bobbin being substantially the same when a full bobbin engages the detector member, and the relative rate of motion of the bobbin with respect to the weighted means and detector member increasing as the diameter of the bobbin diminishes.

2. In weft detecting mechanism for a loom having a lay, a detector member, a device interposed between the lay and the detector member and moving about a pivot, a pair of spaced elements on said device, one element lying on one side of the pivot of the device adjacent the lay to be engaged by the latter and another element lying on the other side of the pivot and remote from the lay, means on the lay to engage the element adjacent the lay, and connections between the element remote from the lay and the detector member, the element adjacent the lay when engaged by the means on the lay moving at a greater rate of motion than the element remote from the lay, both of said elements moving about the pivot of the device as a center.

3. In a weft detector for a loom having a lay, a detector member, a device pivoted to move about a fixed center, front and rear elements moving with the device, said elements lying on opposite sides of a vertical line passing through the pivot of the device, and connections between the front element and the detector, the rear element being engaged by the lay as the latter advances, the forward movement of the rear element being at a greater rate than the forward movement of the front element.

In testimony whereof I have hereunto affixed my signature.

WALTER H. WAKEFIELD.
